FORREST B. DUNLAP, OF TULSA, OKLAHOMA, ASSIGNOR OF ONE-HALF TO HAROLD L. SULLIVAN, OF TULSA, OKLAHOMA.

PULL-ROD BEARING.

1,420,025.

Specification of Letters Patent. Patented June 20, 1922.

Application filed April 22, 1920. Serial No. 375,802.

To all whom it may concern:

Be it known that I, FORREST B. DUNLAP, a citizen of the United States, residing at Tulsa, in the county of Tulsa and State of Oklahoma, have invented certain new and useful Improvements in Pull-Rod Bearings; and I do hereby declare the following to be a full, clear, and exact description of the invention, such as will enable others skilled 10 in the art to which it appertains to make and use the same.

The object of the invention is to provide a simple and efficient pull rod bearing for oil well pump rigs and the like wherein the friction ordinarily incident to the operation of the pump by reason of the support of the pull rod between the motor or pump operating mechanism and the well may be minimized to secure the maximum efficiency of 20 the pumping mechanism or of the power expended in connection with the operation of pumping by the motor, and furthermore to facilitate the mounting or running of the pull rod in arranging the pump mechanism 25 for operation, and with these objects in view the invention consists in a construction and combination of parts of which a preferred embodiment is shown in the accompanying drawing, wherein—

30 Figure 1 is a general view of a pumping plant showing the pull rod supported at intervals by bearings embodying the invention.

Figure 2 is a detail view in section of one of the pull rod bearings.

35 Figure 3 is a side view of the same.

It is common in the oil field to operate a number of pumps from a common plant or motor located at considerable distances from the wells and to communicate motion from 40 the engine or motor to the several pumps by means of pull rods 10 which are extended horizontally or in substantially horizontal directions radially from the engine or motor, and it is with a view to minimizing the friction 45 due to the movement of the pull rod at the necessary points of support thereof between the motor and the well that the device embodying the invention has been designed, and in the form illustrated in the drawings 50 the same consists essentially of a standard 11 preferably tubular and consisting of a pipe of suitable dimensions which may readily be driven into the ground at any desired point and at intervals throughout the length of the

run of the pull rod, and heads 12 which are 55 swiveled upon these standards and carry grooved rollers 13 for guiding and supporting pull rods. As shown the head is provided with a depending spindle portion 14 fitted in the upper end of the tubular standard and held from downward displacement by any suitable means such as a shoulder 15 thereon, and a looped housing 16 rising from the spindle and supporting a tubular shaft 17 extending through a bushing 18 60 carried by the roller, suitable terminal washers 19 being provided upon the bushing to hold the side surfaces of the roller out of frictional contact with the inner surfaces of the walls of the housing. The shaft upon 70 which the roller is mounted is preferably tubular as indicated and connected with one end thereof is a grease cup 20 by which a lubricant may be forcibly fed into the bore of the shaft to be expelled through a feed 75 opening 21 formed in the wall of the shaft within the bushing to minimize the friction of the roller thereon. Anti-friction rollers 22 may also be interposed between the bushing and the shaft to still further reduce the 80 friction, and if desired the lower portion of the housing may be closed at its ends to form an oil pan 23 in which the lower portion of the periphery of the wheel dips, so that as the latter turns it will carry the oil to the 85 surface which is traversed by the pull rod.

By means of such a construction and arrangement, after the erection of the apparatus and the initial oiling of the same, or the adjustment of the grease cup, the operation may continue indefinitely without further consideration by the attendant and without the disadvantages incident to heating and consequent injury which is common 90 in the ordinary practice. It will be obvious 95 that the device may be set up at any desired intervals and may be removed and redisposed in relation to other wells with a minimum effort and loss of time and the direction of movement of the pull rod will insure the 100 maintenance of the head in the upper directional position with reference thereto without requiring the attention of the operator.

What is claimed is:—

1. A bearing for a well pump pull rod comprising a roller, a shaft to support the roller, a housing for the roller having spaced side

105

members, said shaft being mounted in said side members, and means integral with said side members substantially closing the sides of the housing intermediate the side members and terminating relatively close to the periphery of the roller to form a reservoir to lubricate said periphery.

2. A bearing for a well pump pull rod comprising a substantially cylindrical shank 10 to swivelly mount it, an arch shaped housing integral with and rising from the shank, a roller, a shaft to support the roller in the housing, and means integral with the shank and housing partly closing the sides of the 15 housing and terminating relatively close to

the periphery of the roller to form a reservoir for oil to lubricate said periphery.

3. A bearing for a well pump pull rod comprising a head, a roller thereon, a tubular shaft supporting the roller having a closure 20 head at one end, an oil cup at the other end, and means of escape for oil through the shaft to journal the surface of the roller.

In testimony whereof I affix my signature in presence of two witnesses.

FORREST B. DUNLAP.

Witnesses:

W. E. DAVIDSON,
MASON KITTESS.
